ALBERT AKERHIELM, OF CHICAGO, ILLINOIS, ASSIGNOR, BY MESNE ASSIGNMENTS, TO
UNI-MOTION DOOR HANDLE CO., OF CHICAGO, ILLINOIS, A CORPORATION OF
ILLINOIS.

DOOR-CATCH-OPERATING MECHANISM.

1,158,881.

Specification of Letters Patent.

Patented Nov. 2, 1915.

Application filed December 2, 1914. Serial No. 875,097.

To all whom it may concern:

Be it known that I, ALBERT AKERHIELM, a subject of the King of Sweden, residing at Chicago, in the county of Cook and State of Illinois, have invented certain new and useful Improvements in Door-Catch-Operating Mechanisms, of which the following is a specification.

My invention relates to an improved form 10 of operating mechanism for door catches, particularly adapted for use in connection with the form of catches or combined catches and locks commonly installed in store doors and usually operable by the depression of a pivoted lever extending from each face of the door. Catches of this construction are common in the art, and are found either in the form of catches alone or more usually in the form of combined 15 catches and locks. Catches of this general kind are usually housed in a casing, one edge of which is cut away to expose the end of a plunger contained in the casing for operating the catch. While my invention does 20 not pertain directly to the catch construction or its housing, it is so intimately associated therewith and depends upon it for its utility that I have shown in the drawings a common form of catch construction which is described in detail below in relation to my improved operating mechanism.

It is a purpose of my invention to provide an operating mechanism in which the pivoted lever construction, as well as all devices 35 of any kind other than the handle of the door itself, are eliminated, and the handle, while it has every appearance of being simply for the purpose of moving the door to its open or closed position, as desired, in 40 reality constitutes also the operating mechanism for the catch by being mounted in suitable supporting plates so that it is capable of slight motion relatively to the door, sufficient, however, to operate the catch by 45 means of suitable devices to be described.

One of the principal objects of my invention is to construct a combined handle and catch-operating mechanism of the kind referred to that may readily be mounted upon 50 a door already provided with a catch of the kind referred to without in any way disturbing the catch casing and affording when installed a simpler and more effective operating device than is provided by means of 55 the ordinary pivoted lever construction.

The catch-operating mechanism forms no part of the catch construction or its housing and yet may be readily mounted upon the door so as to operate any particular form of standard catch of the class referred to. As 60 catches for store doors are usually provided with combined locks and catches, the key receptacles extending outwardly from the catch and lock housing with which locks of this kind are ordinarily provided afford a 65 convenient means for engaging the mounting plates of my improved handle construction, so that even an inexperienced person may readily mount the handle and operating device upon a door containing the lock 70 and catch already in use.

The several drawings illustrating my invention are as follows:

Figure 1 shows a part of a door in front elevation with my handle mounted thereon; Fig. 2 is a view taken from the left of the parts shown in Fig. 1; Fig. 3 is a view partially in section of a portion of the door and catch shown in Fig. 1, the section being taken along a plane parallel with the outer surface of the door; Fig. 4 shows in a vertical section taken at right-angles to the plane of the outer face of the door through the center line of the handle and shows a part of the handle construction and the relation 80 of the operating mechanism to the lower portion of the catch casing; and Fig. 5 shows in a view similar to Fig. 4 a modified form of mechanism for operating the catch by movement of the handle rod. 85

Similar numerals refer to similar parts throughout the several views.

As shown in Figs. 1 and 2, the door 1 is provided with a combined catch and lock 2 having outwardly extending key receptacles 3 and 4 from either side thereof. The mounting plates 5 and 6 secured upon opposite faces of the door by screws, as indicated, are provided near their upper ends with circular openings which fit the key extensions 100 3 and 4. The plates 5 and 6 have reciprocally mounted in them at their central and lower portions two cylindrical rods or tubes 7 and 8, the outer ends of which are rigidly connected together in any desired manner by 105 the handles 9 and 10. Thus the rods 7 and 8 and the handles 9 and 10 together constitute a rigid rectangular framework guided by the mounting plates 5 and 6 so as to be freely capable of a limited amount of motion 110

through the door, in one direction to actuate the catch and in the other direction to release the catch. The lower rod 8 is preferably provided with stops 11 for limiting the motion of the rod in either direction, while the construction of the upper rod 7 between the plates 5 and 6 is best shown in Fig. 4 as follows: On its upper surface and normally resting against the plate 5 is an operating cam 12, which is rigidly secured to the rod 7 in any desired manner, as, for example, by soldering, brazing, or by screws or rivets, or any desired combination of these means. The point of the cam or wedge 12, which is preferably made of steel, is normally in close proximity to the lower edge of the plunger 13 mounted so as to reciprocate vertically in the catch casing 14, as shown in Fig. 3. The upper end of the plunger 13 engages a lever 15 pivotally mounted in the casing 14 at 16, and the upper end of this lever in turn engages a disk 17 secured to the right-hand end of the catch rod or bar 18, to the left-hand end of which the beveled catch 19 is secured. A compression spring 20 surrounds the rod 18 with its ends resting against the right-hand face of the catch 19 and the left-hand face of an abutment 21 carried by the casing 14 so as to maintain the catch in its left-hand or outer position unless the plunger 13 is operated. It will be observed that the spring 20 also serves to normally hold the lever 15 and the plunger 13 in the position indicated in Fig. 3. The plates 5 and 6 and the handles 9 and 10 are preferably similar, although they need not necessarily be so, and when similar, the only care that need be exercised in mounting the device upon a door is that the cam 12 shall be located on the side of the catch casing in the direction of motion of closing the door. A spring 22 is secured, as indicated, to the inner face of the plate 5, and its ends engage suitable openings therefor in the rods 7 and 8 to normally hold the rods in the position indicated in Figs. 2 and 4. While this spring is shown as a flat leaf spring, it will be understood that any form of spring or springs may be employed for this purpose without departing from the spirit of my invention. The catch-operating device is preferably provided with a lock 23 pivoted to the plate 5 at 24 and constructed so that when it is moved to the position indicated in full lines in Figs. 1 and 2 it enters a slot provided therefor in the lower surface of the rod 8 so as to prevent movement of the handle construction. When moved to its position indicated in dotted lines it releases the handle and permits operation of the catch. It will be understood that this lock may be placed upon either of the plates 5 and 6, and that its position is determined by the direction in which the door swings, the lock being always located of course on the

inside of the room closed by the door. It is not essential that the lower rod 8 should be engaged by the lock, as the same may be, if preferred, located so as to correspondingly engage the rod 7. Furthermore, the lock 23 may engage its coöperating rod so as to retain the same in any desired position. 70

It will be understood that catches of the kind described are usually provided with lock bolts, as indicated at 25, to operate 75 which key-holders 3 and 4 of one kind or another project from the combined catch and lock casing 2, and since the combined catches and locks are made of standard size, the proper location of the handle and operating rod 7 is determined by the openings formed in the plates 5 and 6 to surround and engage the key-holders 3 and 4 so that the proper location of the catch-operating mechanism upon a door provided with the standard catch construction is a simple matter. Little expense is involved in mounting the operating mechanism upon a door for the reason that all that is required is to bore the two holes through the door for the accommodation of the rods 7 and 8 and cut the necessary clearance for the spring 22 and cam 12. 90

It will be understood that there are forms of catch constructions involving different kinds of mechanism between the actuating plungers and the catches, but that most of these various constructions are built of standard dimensions so that the improved catch-operating mechanism above described 95 is adapted to operate any of them. While the cam 12 serves as a stop for limiting the motion of the rod 7, it is in practice advisable to provide additional stops in the way of projecting screws or pins 26, as indicated in 100 Fig. 4, for limiting this motion. 105

The operating handles may be given a wide variety of constructions, the essential feature in carrying out my invention being that a part of this handle construction shall 110 be a rod carrying or coöperating with devices for operating the plunger of the catch construction, and the handle construction and its connecting rods may be made of solid or tubular rods, as desired, with any particular kind of ornamentation that may suit the fancy of the maker or user. It is immaterial whether the operating rod 7 be of round or of other cross-section, although it is preferable to have it round to facilitate 115 the construction. It is also not necessary in carrying out my invention to employ the specific cam construction shown, as other forms of operating mechanism may be employed, such, for example, as the lever arrangement shown in Fig. 5, in which the bell-crank lever 27 is pivotally mounted at 28 upon the plate 5^a and engaged on the right-hand side of its lower end by a stop 29, which, when the rod 7^a carrying said 120 125 130

stop 29 is moved to the left moves the lever 27 so as to push the plunger 13^a in an upward direction, and thus actuate the catch. It is also immaterial in what manner the 5 rods 7 and 8 are mounted in the plates 5 and 6, as such mounting may be formed either by portions of the plates themselves without special reinforcement or bushings of one kind or another may be carried by the plates 10 5 and 6 to afford any desired degree of bearing surface for said rods 7 and 8.

From the above it will be seen that by my 15 invention I provide an operating mechanism for standard door catches which is entirely 20 separate from the catch construction and at the same time is of a type requiring the use in connection with the mounting plates of only some form of handle used to move the door to its open or closed position, and that 25 said handle, without any thought on the part of the operator, by the effort exerted upon it to open or close the door automatically by the same motion actuates the catch, removing it from engagement with its striking plate in opening the door, and for the opposite direction of motion of the handle releasing the catch so that it again engages the striking plate to hold the door in its closed position; and, furthermore, that 30 while the operating mechanism is separate from and independent of the catch construction, where the catch construction is also provided with a lock, as is ordinarily the case, the location of the operating mechanism upon a door is accurately and 35 conveniently determined by projecting parts of the lock-operating mechanism of the combined lock and catch so that the operating mechanism may be properly mounted in 40 place without careful measurements or workmanship.

While I have shown my invention in the particular embodiments above described, it will be understood that I do not limit myself 45 to these constructions, as my invention will be realized by the use of any equivalent devices or means for accomplishing the described results.

What I claim is:

- 50 1. In an operating mechanism for combined standard catches and locks, the combination of a pair of mounting plates one for location upon either side of a door and having openings therethrough for engaging key-holders extending from the combined catch and lock, a pair of substantially horizontal rods extending through said mounting plates and capable of being reciprocated relatively to the mounting plates, a pair of handles connecting the ends of the rods, a cam carried by one of the rods for engaging and operating the catch of the combined catch and lock, and a spring for holding the cam in its inoperative position, the mounting plates and parts carried thereby being
- 55
- 60
- 65

entirely outside and independent of the combined catch and lock casing.

2. In an operating mechanism for combined standard catches and locks, the combination of a pair of mounting plates one for location upon either side of a door and having openings therethrough for engaging key-holders extending from the combined catch and lock, a pair of substantially horizontal rods extending through said mounting plates and capable of being reciprocated relatively to the mounting plates, a pair of handles connecting the ends of the rods, a cam carried by one of the rods for engaging and operating the catch of the combined catch and lock, a spring for holding the cam in its inoperative position, the mounting plates and parts carried thereby being entirely outside and independent of the combined catch and lock casing, and a lock for preventing reciprocation of said horizontal rods relatively to the mounting plates.

3. In an operating mechanism for combined standard catches and locks, the combination of a pair of mounting plates one for location upon either side of a door and having openings therethrough for engaging key-holders extending from the combined catch and lock, a pair of substantially horizontal rods extending through said mounting plates and capable of being reciprocated relatively to the mounting plates, a pair of handles connecting the ends of the rods, devices operated by one of the rods for actuating the catch of the combined catch and lock, and a spring for holding said devices in inoperative position, the mounting plates and parts carried thereby being entirely outside and independent of the combined catch and lock casing.

4. In an operating mechanism for combined standard catches and locks, the combination of a pair of mounting plates one for location upon either side of a door and having openings therethrough for engaging key-holders extending from the combined catch and lock, a pair of substantially horizontal rods extending through said mounting plates and capable of being reciprocated relatively to the mounting plates, a pair of handles connecting the ends of the rods, devices operated by one of the rods for actuating the catch of the combined catch and lock, a spring for holding said devices in inoperative position, the mounting plates and parts carried thereby being entirely outside and independent of the combined catch and lock casing, and a lock for preventing reciprocation of said horizontal rods relatively to the mounting plates.

5. In an operating mechanism for combined standard catches and locks, the combination of a pair of mounting plates one for location upon either side of a door and

provided with openings for engaging key-holding means projecting from the combined catch and lock to locate the plates upon the door, a handle located outside of each mounting plate, a rod connecting the handles and capable of longitudinal reciprocation through bearings therefor in the mounting plates, and a cam carried by the rod for operating the catch of the combined catch and lock, the parts constituting said combination being independent of the catch and lock casing.

6. In an operating mechanism for combined standard catches and locks, the combination of a pair of mounting plates one for location upon either side of a door and provided with openings for engaging key-holding means projecting from the combined catch and lock to locate the plates upon the door, a handle located outside of each mounting plate, a rod connecting the handles and capable of longitudinal reciprocation through bearings therefor in the mounting plates, and mechanism in operative relation to the rod adapted for movement by reciprocation by said rod to actuate the catch of the combined catch and lock, the parts constituting said combination being independent of the catch and lock casing.

7. In an operating mechanism for combined standard catches and locks, the combination of a pair of mounting plates one for location upon either side of a door and provided with openings for engaging key-holding means projecting from the combined catch and lock to locate the plates upon the door, a handle located outside of each mounting plate, a rod connecting the handles and capable of longitudinal reciprocation through bearings therefor in the mounting plates, a cam carried by the rod for operating the catch of the combined catch and lock, and a spring for holding the rod in a position to release said catch, the parts constituting said combination being independent of the catch and lock casing.

8. In an operating mechanism for combined standard catches and locks, the combination of a pair of mounting plates one for location upon either side of a door and provided with openings for engaging key-holding means projecting from the combined catch and lock to locate the plates upon the door, a handle located outside of each mounting plate, a rod connecting the handles and capable of longitudinal reciprocation through bearings therefor in the mounting plates, mechanism in operative relation to the rod adapted for movement by reciprocation by said rod to actuate the catch of the combined catch and lock, and a spring for holding the rod in a position to release said catch, the parts constituting said combination being independent of the catch and lock casing.

9. In an operating mechanism for standard catches having a member located at one edge of the catch casing for operating the catch, the combination of a pair of mounting plates, a rod supported in the mounting plates and capable of longitudinal reciprocation therethrough, and mechanism associated with the mounting plates for operating said member when the rod is reciprocated through the plates, the parts constituting said combination being independent of the catch casing.

10. In an operating mechanism for standard catches having a member located at one edge of the catch casing for operating the catch, the combination of a pair of mounting plates, a rod supported in the mounting plates and capable of longitudinal reciprocation therethrough, mechanism associated with the mounting plates for operating said member when the rod is reciprocated through the plates, and a spring for holding the rod in a position to release said member, the parts constituting said combination being independent of the catch casing.

11. In an operating mechanism for standard catches having a member located at one edge of the catch casing for operating the catch, the combination of a pair of mounting plates, a rod supported in the mounting plates and capable of longitudinal reciprocation therethrough, and a cam carried by the rod for moving said member when the rod is reciprocated through the plates, the parts constituting said combination being independent of the catch casing.

12. In an operating mechanism for standard catches having a member located at one edge of the catch casing for operating the catch, the combination of a pair of mounting plates, a rod supported in the mounting plates and capable of longitudinal reciprocation therethrough, a cam carried by the rod for moving said member when the rod is reciprocated through the plates, and a spring for holding the rod in a position to release said member, the parts constituting said combination being independent of the catch casing.

13. In an operating mechanism for combined standard catches and locks, the combination of a pair of mounting plates one for location upon either side of a door and having openings therethrough for engaging key-holders extending from the combined catch and lock, a pair of substantially horizontal rods extending through said mounting plates and capable of being reciprocated relatively to the mounting plates, a pair of handles connecting the ends of the rods, a cam carried by one of the rods for engaging and operating the catch of the combined catch and lock, a spring for holding the cam in its inoperative position, the mounting plates and parts carried thereby

being entirely outside and independent of the combined catch and lock casing, and stops carried by the horizontal rods for limiting the motion of the rods through the 5 mounting plates.

14. In an operating mechanism for combined standard catches and locks, the combination of a pair of mounting plates one for location upon either side of a door and having 10 openings therethrough for engaging key-holders extending from the combined catch and lock, a pair of substantially horizontal rods extending through said mounting plates and capable of being reciprocated 15 relatively to the mounting plates, a pair of handles connecting the ends of the rods, a cam carried by one of the rods for engaging and operating the catch of the combined catch and lock, a spring for holding the 20 cam in its inoperative position, the mounting plates and parts carried thereby being entirely outside and independent of the combined catch and lock casing, and a lock for preventing reciprocation of the horizontal 25 rods through the mounting plates.

15. In an operating mechanism for standard catches having a member located at one

edge of the catch casing for operating the catch, the combination of a mounting plate, a rod supported by the mounting plate for reciprocation longitudinally of said rod, and mechanism associated with the mounting plate for operating said member when the rod is reciprocated, said combination being independent of the catch casing. 30

16. In an operating mechanism for standard catches having a member located at one edge of the catch casing for operating the catch, the combination of a mounting plate, a rod supported by the mounting plate for reciprocation longitudinally of said rod, mechanism associated with the mounting plate for operating said member when the rod is reciprocated, and a lock for preventing reciprocation of the rod, said combination 40 being independent of the catch casing. 45

In witness whereof, I hereunto subscribe my name this 27th day of November, A. D., 1914.

ALBERT AKERHIELM.
